CLAIM

The ornamental design for a telescope, as shown, and described.

DESCRIPTION

FIG. 1: A top plan view of a telescope with the tube thereof being shown in broken lines since it is not part of the design;

FIG. 2: A perspective view thereof;

FIG. 3: A left side view thereof;

FIG. 4: A front view thereof;

FIG. 5: A right side view thereof;

FIG. 6: A rear view thereof;

FIG. 7: A top plan view similar to FIG. 1 but with the hand control unit removed;

FIG. 8: A perspective view similar to FIG. 2 but with the hand control unit removed;

FIG. 9: A left side view similar to FIG. 3 but with the hand control unit removed;

FIG. 10: A front view similar to FIG. 4 but with the hand control unit removed;

FIG. 11: A right side view similar to FIG. 5 but with the hand control unit removed; and,

FIG. 12: A rear view similar to FIG. 6 but with the hand control unit removed.
